(57) **CLAIM**

The ornamental design for an integrated antenna with connector, as shown and described.

DESCRIPTION

FIG. 1 is a perspective view of an integrated antenna with connector, showing our new design;

FIG. 2 is a front side elevation view of the integrated antenna with connector of FIG. 1;

FIG. 3 is a back side elevation view of the integrated antenna with connector of FIG. 1;

FIG. 4 is a right side elevation of the integrated antenna with connector of FIG. 1;

FIG. 5 is a left side elevation view of the integrated antenna with connector of FIG. 1;

FIG. 6 is a bottom plan view of the integrated antenna with connector of FIG. 1; and,

FIG. 7 is a top plan view of the integrated antenna with connector of FIG. 1.

The features shown in broken lines in the various figures are for illustrating environmental structure and form no part of the claimed design. More generally, the invention pertains to an ornamental design for an article of manufacture. The article is not limited to the scale shown herein. As indicated in the title, the article of manufacture to which the ornamental design has been applied is an integrated antenna with connector.

1 Claim, 4 Drawing Sheets
